ASH TRAY

Alvin L. Saeks, 7542 Wellington Way, Clayton, Mo.

Filed May 8, 1957, Ser. No. 46,063

Term of patent 14 years

(Cl. D85—2)

FIG. 1.

FIG. 2.

FIG. 3.

FIG. 4.

FIG. 5.

FIG. 1 is a perspective view of an ash tray embodying my new design;

FIG. 2 is a reduced top plan view thereof;

FIG. 3 is a reduced bottom plan view thereof;

FIG. 4 is a reduced end elevational view thereof; and

FIG. 5 is a reduced front elevational view thereof.

I claim:

The ornamental design for an ash tray, substantially as shown.
